UNITED STATES PATENT OFFICE.

LOUIS STEINBERGER, OF NEW YORK, N. Y.

RAIL-SUPPORT.

SPECIFICATION forming part of Letters Patent No. 759,767, dated May 10, 1904.

Application filed January 7, 1904. Serial No. 188,052. (No model.)

To all whom it may concern:

Be it known that I, LOUIS STEINBERGER, a citizen of the United States, and a resident of the city of New York, borough of Brooklyn, 5 in the county of Kings and State of New York, have invented a new and Improved Rail-Support, of which the following is a full, clear, and exact description.

My invention relates to an insulated support, and is particularly adapted for use in supporting and insulating a third rail of an electric railway, although it will be evident that it may be used for insulating and supporting various other electric conductors.

15 The object of my invention is to provide an insulated conductor-support which will permit the rail ample freedom of movement in any direction, thereby providing for the expansion and contraction of the rail and for the vertical 20 movements of the ties.

A further object is to relieve the supports of undue strains and permit the rail to accommodate itself to the various positions of the collector-shoe, thereby insuring a constant and 25 perfect contact.

Reference is to be had to the accompanying drawings, forming a part of this specification, in which similar characters of reference indicate corresponding parts in all the figures.

30 Figure 1 is a perspective view showing my invention as applied to a rail. Fig. 2 is a vertical cross-section through the same, showing the rail in its normal position. Fig. 3 is a fragmentary cross-section somewhat similar to Fig. 2, 35 but showing the rail as careened in a lateral direction owing to the depression of the ties or the pressure of the collector-shoe. Fig. 4 is an inverted plan or bottom view of the weather-shield and rocker member, and Fig. 5 is a detail showing in perspective view the bearing- 40 plate and the boss whereby the same is mounted.

The cross-tie is shown at 1, and mounted upon it is a bed-plate 2, preferably of metal, 45 provided with a flange 3, this flange being secured in position by means of bolts or spikes 4. The bed-plate 2 is of conical form and hollow. Resting upon it and disposed partially within it is a portion 5 of a double-ended cone, 50 the other portion, 6, being provided with an annular flange 7, which overhangs the upper

annular edge of the bed-plate 2, as shown more particularly in Figs. 2 and 3. This double-ended cone is of insulating material and is substantially hollow, as indicated in Figs. 2 and 55 3, and into it projects a boss 8, carrying upon its upper portion a bearing-plate 9, integral therewith, this bearing-plate having slots 10 or equivalent mutilations. A rocker 11, preferably circular, is provided with a hood 12, 60 depending therefrom, and is also provided with guide-webs 13, these webs depending directly from the hood 11 and being integral therewith, as indicated in Figs. 2, 3, and 4. Lugs 14 are also integral with the rocker 11 65 and may be bent inwardly toward each other, so as to clamp the base 15 of the rail 16. The rocker 11 is provided with a rotund or convex portion 17, this portion having substantially the form of a plano-convex lens, so as 70 to engage the bearing-plate 9 and virtually form thereupon a fulcrum which permits the rail to move relatively to the support in a plurality of directions. I find that the rail has comparatively little tendency to rock in any 75 other direction than the one crossing the general direction of the length of the rail, as indicated in Fig. 3, though it may incline the rocker member when the rail moves longitudinally, owing to expansion or contraction. 80

I do not limit myself to the circular form for the rotund portion 17. Neither do I limit myself in all cases to a rocker having a convex portion. Neither do I limit myself to the means for fastening the rail upon a rocker, 85 nor for supporting the rocker. Neither do I limit myself to making the parts 2, 5, 8, and 9 detachable. Any or all of the parts described may be varied within reasonable limits without departing from the spirit of my 90 invention.

It will be noted that the hood 12 covers the upper end of the insulation at all times, notwithstanding the fact that the rail may rock or move in a lateral direction within wide 95 limits. The rain or other moisture is therefore unable to wet the contact-plate 9 or to insinuate itself into any crevice or seam connected with the apparatus. So, also, the flange 7, of insulating material, protects the junction between the insulation and the bed-plate 2 in order to prevent the moisture from soaking 100

into the seams and crevices. In fact, the umbrella-like structure of the hood 12 and of the flange 7 makes the apparatus practically impermeable to moisture, so that the insulating material used may, if desired, be of a comparatively cheap grade. The guide-webs 13 work loosely within the slots 10, and therefore allow the rail to creep slightly in the general direction of its length and also allow it a freedom of movement in any and all directions. The result is that while the rail is so supported as to exhibit considerable strength it has nevertheless an adequate degree of flexibility, so greatly desired by persons operating in this art.

It will be noted that the bed-plate 2, the insulation resting thereupon, and the bearing-plate 9 together constitute a composite pedestal the parts of which are readily detachable and are consequently easily replaced when worn out or destroyed.

When the general position of the rail is disturbed to the slightest extent, the tendency of the rail is to automatically correct its position. 25 It therefore rests in stable equilibrium.

Having thus described my invention, I claim as new and desire to secure by Letters Patent—

1. A rail-support, comprising a rocker to be connected with a rail, said rocker having a portion of substantially the shape of a plano-convex lens for the purpose of engaging a supporting-surface and thereby sustaining said rail in stable equilibrium.

2. A rail-support, comprising a rocker having a portion for engaging a rail, and also having a rotund portion, the curvature of said portion extending in all directions for the purpose of enabling said rail to rock in various directions independently of each other.

40 3. A rail-support, comprising a pedestal provided with a bearing-plate, and a rocker provided with a portion for engaging a rail, and also with a surface for engaging said bearing-plate, so as to support said rail in stable equilibrium, said rocker being further provided with guide mechanism for maintaining it substantially in a predetermined position relatively to said bearing-plate.

45 4. A rail-support, comprising a metallic member to be connected with a tie, an insulating member to be connected with said metallic member, a bearing-plate for resting upon said insulating member, and a metallic member to be connected with a rail and resting in stable equilibrium upon said bearing-plate, said last-mentioned metallic member being provided with a surface for engaging said rail.

50 5. A rail-support, comprising a bearing-plate provided with mutilations, means for sustaining said bearing-plate, and a rocker loosely mounted upon said bearing-plate and provided with guide members loosely engaging said mutilations, said rocker being further provided with a portion for engaging a rail.

6. A rail-support, comprising a hollow me-

tallic member, an insulating member disposed partially within the same and provided with a portion projecting upwardly therefrom, a bearing-plate connected with said insulating material and resting thereupon, and mechanism connected with said bearing-plate for supporting a rail thereupon in stable equilibrium. 70

7. A rail-support, comprising a metallic member of frusto-conical form, an insulating member mounted thereupon and having a portion of substantially frusto-conical form, said metallic member and said insulating member together forming an elongated cone frustum, a bearing-plate mounted upon said insulating member, and means for supporting a rail in stable equilibrium upon said elongated cone frustum. 80

8. A rail-support, comprising a metallic member provided with a flange to be secured upon a cross-tie, and also provided with an aperture, a member of insulating material disposed partially within said aperture, a bearing-plate connected with said member of insulating material and provided with a bearing-surface, and a rocker resting upon said bearing-surface and provided with a portion for engaging a rail. 85

9. A rail-support, comprising a bearing-plate provided with a boss, mechanism disposed below said bearing-plate and engaging said boss for the purpose of supporting said bearing-plate, said bearing-plate being provided with slots, and a rocker provided with guide-webs loosely engaging said slots, said rocker being further provided with mechanism for engaging the base of a rail. 95

10. As an article of manufacture, a rail-rocker comprising a metallic member provided with a surface for engaging a rail, and also provided with a rotund portion, said metallic member being further provided with a hood. 105

11. As an article of manufacture, a rail-rocker comprising a metallic member having a portion to be engaged by a rail, and also having a portion for engaging a bearing-surface and thereby supporting said rail in stable equilibrium, said metallic member being further provided with members for engaging a stationary mechanism and thereby loosely holding said metallic member in a general predetermined position. 115

12. As an article of manufacture, a rail-rocker comprising a metallic member provided with a portion to be engaged by a rail, and also provided with a portion for engaging a support and thereby sustaining said rail in stable equilibrium, said metallic member being further provided with a weather-shield and with guiding members for holding said metallic member substantially in a predetermined position. 120

13. As an article of manufacture, a rail-rocker consisting of a metallic member provided with a portion to be secured to a rail, and also with a portion for engaging a bear- 130

ing-surface for the purpose of supporting said rail in stable equilibrium, said metallic member being provided with a hood depending therefrom and serving as a weather-shield.

5 14. As an article of manufacture, a rail-rocker consisting of a metallic member provided with a convex face for engaging a bearing-surface, and also provided with guide-webs disposed upon either side of said convex 10 face for guiding said convex face relatively to said bearing-surface.

15. As an article of manufacture, a rail-rocker comprising a hollow metallic member provided integrally with a convex face, said member being further provided with a surface for engaging a rail.

16. As an article of manufacture, a rail-rocker comprising a metallic member of substantially circular conformity, said metallic 20 member being provided with a hood integral therewith, and with a rotund bearing portion disposed centrally within said hood, said metallic member being further provided with means for engaging a rail.

25 17. As an article of manufacture, a rail-rocker comprising a member provided with a portion for engaging a rail, and also provided with a rotund rocker portion.

18. A rail-support, comprising a rocker 30 member and a base portion, and an insulating member interposed between said rocker member and said base portion.

35 19. A rail-support, comprising a rocker member, a bearing member and a base portion, and an insulating member engaging said bearing member and said base portion.

20. A rail-support, comprising a metallic rocker member and a metallic base portion, and an insulating member interposed between 40 said rocker member and said base portion.

21. A rail-support, comprising a metallic rocker member, a metallic bearing member and a base portion, and an insulating member engaging said bearing member and said base 45 portion.

22. As an article of manufacture, a rail-rocker comprising a member provided with a portion for engaging a rail and with a convex rocker portion, said member being further provided with a weather-shield.

23. A rail-support, comprising a rocker provided with mechanism for engaging a rail, and also provided with a portion for engaging a supporting-surface and thereby sustaining the 55 rail in stable equilibrium, said rocker being further provided with a weather-shield.

24. A rail-support, comprising a convex rocker provided with lugs for engaging a rail, said rocker being provided with a weather-shield, and with a portion for engaging a supporting-surface, and thereby sustaining the rail in stable equilibrium.

60 25. A rail-support, comprising a convex rocker provided with means for connecting a

rail thereto, said rocker being further provided with a weather-shield having the form of a downwardly-extending hood.

26. A rail-support, comprising a convex rocker provided with a weather-shield and with a portion for engaging a support disposed within said weather-shield, thereby sustaining said rocker in stable equilibrium, and means for connecting a rail to said rocker.

27. A rail-support, comprising a pedestal, mechanism connected therewith and provided with a rocker for supporting a rail in stable equilibrium, and a weather-shield for protecting said last-mentioned mechanism from the action of the weather.

28. A rail-support, comprising a member provided with a bearing-surface, mechanism connected therewith and provided with a rocker for supporting a rail in stable equilibrium, and a hood encircling said bearing-surface for the purpose of protecting the same from the action of the weather.

29. As an article of manufacture, a rail-rocker comprising a metallic member having a portion for engaging a rail, and also having a portion for engaging a surface, thereby supporting said rail in stable equilibrium, said rocker being further provided with means for securing a rail rigidly thereto, and with a weather-shield.

30. A rail-support, comprising a rocker member having a single portion of substantially the shape of a plano-convex lens for the purpose of engaging a supporting-surface and thereby sustaining said rocker member in stable equilibrium.

31. A rail-support, comprising a rocker member having means for engaging a rail, and also having a rotund portion, the curvature of said portion extending in all directions for the purpose of enabling said rocker member to rock in various directions, the center of said rotund portion being in alinement with the center of said rail, for the purpose of sustaining said rail in stable equilibrium.

32. A rail-support, comprising a base portion, an insulating member engaging the same, a bearing member engaging said insulating member, and means detachably connected therewith for supporting a rail upon said bearing member in stable equilibrium.

33. As an article of manufacture, a rail-rocker comprising a hollow metallic member provided with a convex portion, said member being further provided with a portion for engaging a rail.

In testimony whereof I have signed my name to this specification in the presence of two subscribing witnesses.
